Fig. 3

FIGURE 1 is a front view of a refrigerator cabinet showing my new design;

FIGURE 2 is a side elevational view thereof; and FIGURE 3 is a top plan view thereof.

The side not shown is substantially like the side shown. The horizontal shading on the front of the refrigerator cabinet indicates contrast, it being understood that said contrast is continuous throughout the panels in which the horizontal shading is shown.

The dominant feature of my design resides in the portions shown in full lines.

I claim:

The ornamental design for a refrigerator cabinet, substantially as shown and described.
